UNITED STATES PATENT OFFICE

1,974,272

SPINDLELESS DISPLAY DEVICE

Herman C. Heineman, Dalton, Nebr.

Application September 5, 1933, Serial No. 688,247

4 Claims. (Cl. 211—131)

- It is the object of this invention to produce a circular display device of wheel-like form which shall be so constructed that it can be rotated in a vertical plane and about its center axis.
- 5 Another object is to produce a spindleless mounting of such construction that the device can be manually rotated with the exertion of very little force, but will not rotate due to a slight unbalancing force.
- 10 A still further object of this invention is to produce a device having a plurality of cup-like receptacles that are suspended from pivots near their open ends and, mounted for rotation about these pivots so that they will always hang with their 15 open ends upwardly, in whichever position the display device may have.

The above and other objects of the invention which may appear as this description proceeds are attained by means of a construction and an 20 arrangement of parts that will now be described in detail, and for this purpose reference will be had to the accompanying drawing in which the preferred embodiment of the invention has been illustrated and in which:

- 25 Fig. 1 is a side elevation of the device; Fig. 2 is an end elevation of the device; and Fig. 3 is a perspective view of a brake mechanism.

In the drawing reference numeral 1 represents 30 a base member, of which the device has two, as shown in Fig. 2. Secured to the base members are pipe fittings of the type usually referred to as T's which are connected by cross bars 3. Extending upwardly from the base members are two 35 U-shaped pipe supports which have been designated by reference numeral 2. These supports are arranged so as to lie in spaced parallel planes as shown in the drawing. Secured to each support are two wheels or pulleys 9 that are provided with rubber tires as shown in Fig. 1. These 40 wheels or pulleys are mounted to rotate about axes 8. Adjustably attached to the U-shaped supports are brake members comprising a strap 10 formed from a flat iron bar whose ends are 45 curved about the sides of the U-shaped supports as indicated by reference numeral 12. One edge of the bar 10 is provided with an outwardly extending flange 11 that is perforated for the reception of bolts 14 which are provided with nuts 15. Secured to the lower ends of the bolts is a brake 50 shoe 16 that can be made from any suitable material such as wood, fiber or rubber composition and may even be made from metal. Springs 17 are located between the brake shoe and the lower 55 surface of flange 11 and are properly tensioned to

produce the friction desired. The object and operation of this brake mechanism will become more apparent as the description proceeds.

Located between the two U-shaped supports is 60 a wheel-like display device which is formed from two circular plates 4. Located between the circular plates and secured to them by bolts 5 are a plurality of cup-like receptacles 6. The bolts 5 extend through the receptacles near their open ends and therefore permit these receptacles to 65 hang vertically at all times, due to the unbalanced position that they assume. When the receptacles are filled with nails or screws or other articles of merchandise, they will be in a highly unbalanced state and will, of course, hang in the manner 70 shown in the drawing.

Since display devices of this kind often become highly unbalanced due to the fact that more articles are taken out from some of the receptacles than from others, they will always turn of their 75 own accord to a position in which the center of gravity is directly beneath the center of rotation, unless means is provided to prevent this rotation due to the unbalanced condition.

In this construction the ordinary spindle or axle 80 employed in connection with similar devices has been dispensed with and in lieu thereof a drum 7 is secured to the outside of each of the circular members 4. The drums 7 are constructed in a manner similar to the ordinary brake drum employed in connection with automobiles and each is provided with a cylindrical flange that projects over the pulleys 9 and the inner surface of which rests on the rubber tires of these pulleys in a manner shown quite clearly in Fig. 1. The brake 85 mechanism is adjusted in such a way that the convex surface of the brake shoe rests on the inner surface of the flange and after the springs have been properly tensioned, the bolts 13 are 90 tightened so as to hold the member 10 in a predetermined position. The tension of the brake is adjusted so that the display device will not turn due to an unbalancing effect resulting from an uneven distribution of the load, but can be freely 95 turned by the salesman and will remain in any position desired due to the friction of the brake and the friction of the mounting employed.

By dispensing with the spindle or shaft, a construction is obtained which can be more easily 105 manufactured and assembled and which also has the requisite friction to prevent accidental rotation as indicated above.

Devices of this kind are especially well adapted for use in hardware stores for the sale of nails, 110

screws and other small articles, but can be employed in many other places.

Having described the invention what is claimed as new is:

- 5 1. A display device comprising, in combination, two spaced supports, a pair of rollers pivotally attached to the inside of each support, a wheel-like member provided on opposite sides with a concentric flange adapted to rest its inner surface on the
- 10 rollers whereby the wheel-like member can be rotated about its center and a friction device secured to one support and cooperating with the inner surface of the flange to retard the rotation of the wheel-like member.
- 15 2. A display device comprising, in combination, two spaced supports, a pair of rollers pivotally attached to the inside of each support, the axes of the rollers being at the same height, a display wheel comprising two circular wheel-like members, means for holding them in spaced relation, and a plurality of cup-like containers located between the wheel-like members, means for pivotally connecting the cups, at their upper ends, to the wheel-like members whereby they will rotate
- 20 about the pivots as the wheel-like member rotates, the wheel-like member having a concentric circular flange on each side, the inner surface of each flange resting on a pair of rollers.
- 25 3. A display device comprising, in combination, two spaced supports, a pair of rollers pivotally attached to the inside of each support, the axes

of the rollers being at the same height, a display wheel comprising two circular wheel-like members, means for holding them in spaced relation, a plurality of cup-like containers located between the wheel-like members, means for pivotally connecting the cups, at their upper ends, to the wheel-like members whereby they will rotate about the pivots as the wheel-like member rotates, the wheel-like member having a concentric circular flange on each side, the inner surface of each flange resting on a pair of rollers and a friction device carried by one of the supports for engagement with the flange surface.

4. A display device comprising, in combination, a display wheel formed from two circular members, spaced apart, and a plurality of cups attached to the circular members by pivot pins located near their open ends, an outwardly extending circular flange on each outer surface of the display wheel, a support for the wheel assembly, the support comprising, a base and two spaced vertical standards, each standard having two rollers pivotally attached to their inner surfaces, the flanges extending onto the rollers in position to be supported thereby whereby the wheel assembly can be turned about its center while supported by the rollers and a friction device attached to one of the supports and positioned to engage the corresponding flange to resist rotation of the wheel assembly.
